UNITED STATES PATENT OFFICE.

FRANK L. GEORGE, OF LOS ANGELES, CALIFORNIA.

DAMPER FOR UPRIGHT-PIANO ACTIONS.

1,353,644.

Specification of Letters Patent.

Patented Sept. 21, 1920.

Application filed September 9, 1919. Serial No. 322,728.

To all whom it may concern:

Be it known that I, FRANK L. GEORGE, a citizen of the United States, residing at Los Angeles, in the county of Los Angeles and

5 State of California, have invented new and useful Improvements in Dampers for Upright-Piano Actions, of which the following is a specification.

10 My invention relates to dampers for actions for upright pianos and consists of the novel features herein shown, described and claimed.

15 A very bad defect in the upright action of to-day, and one causing much annoyance to the pianist, is the impossibility, under the present form of construction, to keep the weight of the touch on the key equalized owing to the constant movement on and off of the loud pedal. The act of putting on the 20 loud pedal moves the damper lever forwardly sufficiently to remove its lower end off the damper spoon, thereby removing the pressure of the damper spring entirely from the spoon, and as this spring pressure constitutes practically one-third of the weight 25 on the key it results in a rapidly alternating light and heavy touch to the performer which is most annoying.

Then too the action regulator has his 30 troubles with adjusting or seating the damper felt on the wire, as the only known method of doing this is to bend the damper wire in the required direction, which is nothing more nor less than a series of experiments, until an approximate seating is attained; this often results in wrenching the 35 impingement of the damper lever and quite frequently causes cracking of the damper flange.

40 Still another serious fault with this form of action is the method of applying a damper spring and hammer spring. To attach the damper spring is a delicate operation and requires considerable and careful labor. Furthermore, the damper is in the 45 way of the screw driver in attaching and removing the spring and consequently, the latter is often broken off entirely. The hammer spring is less defective, its chief 50 fault being in the method of attaching to the spring rail, as the entire strain comes on the wire proper where it is inserted in the spring rail instead of on the coil which

hangs just below the rail, this results in the 55 springs being easily and frequently broken.

My object is to overcome the above objections.

Figure 1 is a fragmentary side elevation of an action for upright pianos having an equalizing damper in accordance with the 60 principles of my invention and showing the damper mechanism in its normal position in full lines and showing its operation in dotted lines, upon application of the loud 65 pedal.

Fig. 2 is a view analogous to Fig. 1 showing the parts in position after the key is struck and before it is released in full lines and in normal position after the key is released in dotted lines.

70 The intermediate action rail 1 has a flange 2 secured against the front side by a screw 3, and the flange 2 extends upwardly above the rail. The upper swing 4 is pivotally connected to the upper end of the flange 2 75 by a pin 3'. The upper end of the sticker 5 is pivotally connected to the forward end of the swing 4 by a pin 6. The sticker 5 has an offset portion 7 above the pin 6. The equalizer spoon 8 extends upwardly from 80 the rear end of the swing 4.

75 The main or large action rail 9 is rigidly mounted above the intermediate action rail 1. A flange 10 is secured to the front side of the action rail 9 by a screw 11 and extends 85 upwardly above the rail. The hammer shank 12 is connected to the flange 10 by a pin 13 and a jack 14 connects with the upper end 7 of the sticker 5 and is positioned to 90 operate upon the hammer shank 12.

95 The damper lever flange 15 is connected to the upper side of the rail 9 by a screw 16 and extends backwardly. The damper lever 17 is connected to the rear end of the flange 15 by a pin 18. The lower end 19 of the damper lever is slightly curved or offset 100 backwardly and a half round extension 20 is formed at the extreme lower end of the portion 19. The equalizer 21 has an ear 22 extending backwardly from its center and the extension 20 is bifurcated to receive the ear 22 and is pivotally connected by a pin 23.

105 The damper lever rod 24 normally bears against the felt 25 secured to the lower rear face of the main action rail 9, and a felt 26 is secured to the upper end of the equalizing

lever equalizer 21 and bears against the rod 24. A felt 27 is secured to the lower end of the equalizing lever equalizer 21 and bears against the spoon 8. The loud pedal rod 28 has a flat fitted upper end 29.

The damper lever rod 24 has crank arms 30 mounted in bearings 31 for supporting the rod, and a crank 32 extends rigidly from the damper lever rod 24 and has an arm 33 at its upper rear end resting upon the end 29 of the loud pedal rod 28; so that when the loud pedal is operated the arm 33 is raised thereby moving the damper lever rod 24 away from the felt 25 and pressing the upper end of the equalizer lever 21 backwardly.

At this time and at all times the lower end of the equalizer 21 is bearing upon the spoon 8 and exerting its pressure upon the 20 key, so that in operating the loud pedal the pressure upon the key is not changed thereby making a uniformity of touch.

The compound compensating spring 34 is formed of hard wire and has an end 35 bearing against the hammer shank 12 above the pin 13, a central coil 36 fitting in a bifurcated bearing 37 at the upper end of the damper lever 17, and an end 38 bearing against the spring rail 39. A pin 40 is inserted through the bearing 37 and through the coil 36.

The damper wire 41 is slidingly mounted in the damper lever 17 and held adjustably in place by a set screw 42. The damper 43 has a socket 44 fitting upon the end 45 of the wire 41 and held adjustably in place by a set screw 46. The end 45 of the wire 41 is bent at right angles to the body of the wire.

40 The lower end of the hammer shank 12 is mounted in a hammer butt 47 and the lower end 35 of the spring fits in a slot formed in the hammer butt 47. The upper end 38 of the spring 34 fits in a slot in the spring 45 rail 39. The spring 34 is placed in position under tension and the lower end 35 is longer from the pin 40 than the upper end 38.

The lower end of the sticker 5 is connected to the lower swing 48 by a pin 49, and the 50 adjusting screw 50 is tapped through the forward end of the swing 48 and rests upon the rear end of the key 51.

The hammer rest 52 is in condition to be engaged by the hammer shank 12 when 55 the key 51 is at rest.

Especial attention is called to the set screws 42 and 46 and to the fact that by manipulating these set screws the damper wire 41 and the damper 43 may be adjusted 60 into any desired position for properly seating the damper relative to the piano wire 53 without bending or twisting the damper wire 41.

Thus I have produced an equalizing 65 damper for actions for upright pianos in

which the damper exerts a constant and unvarying weight upon the key, so that the operation of the loud pedal does not change the touch, and the leading feature of the construction is the equalizing lever 21 pivotally connected at its center to the damper lever 17, one end of the equalizing lever bearing upon the damper rod 24 and the other end of the equalizing lever 21 bearing upon the upper swing 4 and through the 75 upper swing upon the key 51.

Broadly the equalizing damper consists of an equalizer pivotally connected intermediate of its ends to the damper lever with one end of the equalizer bearing upon the 80 damper rod and the other end of the equalizing lever connected to exert its pressure upon the key continuously so that the operation of the loud pedal does not change the touch of the key.

Various changes may be made without departing from the spirit of my invention as claimed.

I claim:

1. A damper for upright piano actions 90 comprising a damper lever, an equalizer pivotally connected intermediate of its ends to the damper lever, a damper rod positioned to carry one end of the equalizer, and a key having means connecting it operatively with 95 the other end of the equalizer.

2. A damper comprising the combination with a collection of upright piano actions, of a damper lever rod mounted to swing forwardly and backwardly, an arm extending from the damper rod, a loud pedal rod engaging the arm, individual dampers having damper levers pivotally mounted, and an equalizer pivotally connected intermediate of its ends to each damper lever, one 100 end of each equalizer bearing upon the damper rod and the other end of each equalizer being connected to exert its pressure upon the corresponding key so that the action of the loud pedal does not change the 110 pressure of the damper upon the key.

3. In a damper for upright piano actions, in combination with a damper lever, a damper lever rod and a key; an equalizer 115 rockingly connected with the damper lever and bearing directly upon the damper lever rod and operatively connected at the other end to bear upon the key during the operation of the rod.

4. In combination in a damper for upright piano actions, a damper lever pivotally mounted intermediate of its ends having a damper fixed to its upper end, a rocking lever fixed to its lower end engaging a damper releasing mechanism at one end 125 thereof, a loud pedal mechanism operatively connected to said damper releasing mechanism, and means connecting the other end of said rocking lever with a key whereby the operation of the loud pedal mechanism 130

operating to release the dampers will exert an unvarying resistance to the movement of the key.

5. A damper for piano actions, comprising a main action rail, a loud pedal mechanism, a damper lever swinging in a vertical plane and pivoted intermediate its ends to said rail, an equalizing lever pivoted intermediate its ends to the damper lever, one 10 end of the equalizing lever being operatively connected to the key and the other end being operatively connected to said loud pedal mechanism whereby substantially constant pressure is exerted on said key, irrespective 15 of the movement of the damper lever.

6. In an upright piano, the combination of a key, a loud pedal mechanism, a damper rod, a damper lever pivoted intermediate its ends to swing in a vertical plane, an equalizing lever pivoted to the damper lever and having one end operatively connected to said key and the other end being operatively connected to said loud pedal mechanism whereby a substantially constant pressure is exerted irrespective of the movement of the damper rod. 20 25

In testimony whereof I have signed my name to this specification.

FRANK L. GEORGE.
